UNITED STATES PATENT OFFICE

2,431,574

MUSICAL CALL SIGNAL TELEPHONE
ATTACHMENT

Herbert D. Mayfield, Middlebourne, W. Va.

Application August 31, 1945, Serial No. 613,721

1 Claim. (Cl. 177—7)

1

The invention relates to a musical telephone call signal telephone attachment, and more especially to a telephone receiving set chime.

The primary object of the invention is the provision of an attachment of this character, wherein the standard telephone call bell of a receiving set will be entirely eliminated and replaces the raucous tone and clatter of the ordinary call bell with a musical tone signal which may be varied to suit the requirements and desires of the individual phone user, the attachment being particularly desirable in an office, home, or other place, and will tend to save jangled nerves caused by sudden blatant ringing of the telephone as is the present-day experience.

Another object of the invention is the provision of an attachment of this character, wherein it replaces the original equipment on the ordinary wall telephone so that a pleasing musical tone audible signal will be had in substitute for bell ringing, thereby leaving one in a relaxed condition to begin conversation rather than startled and perhaps angry as is the case in the call bell ringing now in vogue.

A further object of the invention is the provision of an attachment of this character, which is simple in construction, thoroughly reliable and efficient in operation, trouble free in service, strong, durable, attractive in appearance and with all working parts concealed from view, and inexpensive to manufacture and install.

With these and other objects in view, the invention consists in the features of construction, combination and arrangement of parts, as will be hereinafter more fully described, illustrated in the accompanying drawings, which disclose the preferred embodiments of the invention and pointed out in the claim hereunto appended.

In the accompanying drawings:

Figure 1 is a plan view of the attachment constructed in accordance with the invention, its housing or casing being in horizontal section for detail exposure thereof.

Figure 2 is a sectional view taken on the line 2—2 of Figure 1 looking in the direction of the arrows.

Figure 3 is a sectional view taken on a line 3—3 of Figure 2.

Figure 4 is a perspective view of one of the tone bars of the attachment and detached.

Figure 5 is a perspective view of a tone bar with its hanger associated therewith and removed from the gong bar support shown in Figure 4.

Figure 6 is a fragmentary sectional view taken on a line 6—6 of Figure 5.

2

Figure 7 is a fragmentary perspective view, exploded, showing the bell proper and striker fitting therefor.

Figure 8 is a fragmentary plan view of one of the tone bars showing in detail its fitting with the hanger bracket therefor.

Similar reference characters indicate corresponding parts throughout the several views in the drawings.

10 Referring to the drawings in detail, the attachment constituting the present invention and constructed in accordance therewith comprises an inverted substantially cup-shaped striker or hammer head 10, preferably made from wood, plastic material, hard rubber or other substance and is desired to fit over the ball terminal 11 of the clapper arm or stem 12 and this terminal 11 sounds the bell, not shown, of a telephone set, that is to say, the receiver and transmitter instrument as is now installed for service in an office, home, or other place, the stem or arm 12 being controlled and operated electrically in the usual well known manner. Arranged at opposite side of the clapper stem or arm 12 are the usual 15 signal bell supporting brackets 13 and adjustably fitted in substitute for the bell by fasteners 14 is a bridge or supporting bar 15 and the latter spans the path of movement of the clapper stem or arm 12, as is clearly shown in Figure 3 20 of the drawings.

In the striking path of the terminal 10 on the clapper stem or arm 12 and at opposite sides thereof are tone emitting blades or plate-like keys 16, each through button connection 17 are joined to the terminal ends 18 of an inverted substantially T-shaped hanger bracket 19 having a head clip 20 for adjustable fastening thereof to the bar 15 in relation thereto. The blades or keys 16 are so arranged relative to the clapper stem or arm 25 12 at opposite sides thereof in parallel relation to each other for a striking impact thereon by the member 10 to effect chime-sound audible in substitute for the bell sound. The blades or keys 16 are made from bell metal or other substance 30 producing a pleasing tone and the same are of different but harmonizing tone when sounded. The buttons 17 are in the form of soft rubber 35 gamuts which are inserted in the blades or keys and held fixed therein as best seen in Figure 6 of the drawings.

The clips 20 form friction grips on the bar 15 and the slots 21 receiving the fasteners 14 for connecting such bar 15 to the brackets 13 permit longitudinal displacement or adjustment of such 40 bar for regulating the bridging position thereof.

Encasing the attachment in its entirety is a cover or capping shell 22 so that the attachment is entirely concealed from view and this cover or capping shell is provided with suitable vents 23 so that the chime blades or keys 16 when sounded will enable audibility thereof.

The character of substance from which the member 10 is made will determine the volume of the tone emitted by the chimes and two or three types may be furnished with each attachment so that the patron may vary the tone by removing the cover or shell 22 and changing such member 10 optionally.

In the working of the attachment a combination of musical tones will issue and these may be varied to suit the requirement and desires of the individual phone user.

What is claimed is:

An attachment of the kind described, comprising spaced opposed tone emitting keys, an oscillating clapper having a striking member a resilient shoe frictionally secured on said striking member for engaging the said keys for the sounding thereof, means supporting the keys in their

related positions with respect to said striking member, adjustable frictionally held brackets for the keys included in said supporting means, and a casing for enclosing the striker member keys and supporting means, said means also including arms secured to said brackets, the ends of said arms being held within said tone emitting keys and a resilient material insulating said ends of said arms from said keys, whereby substantially none of the overtones and tones are lost through vibratory transmission through the key supporting links.
